UNITED STATES PATENT OFFICE.

HERMAN A. GILLIAN, OF TOLEDO, OHIO, ASSIGNOR TO THE BACON BROS. COMPANY, OF TOLEDO, OHIO, A CORPORATION OF OHIO.

MATERIAL-HANDLING.

1,391,183.

Specification of Letters Patent. Patented Sept. 20, 1921.

Application filed April 15, 1920. Serial No. 374,061.

To all whom it may concern:

Be it known that I, HERMAN A. GILLIAN, a citizen of the United States of America, residing at Toledo, Lucas county, Ohio, have invented new and useful Material-Handling, of which the following is a specification.

This invention relates to handling material, especially elastic stock, such as knit textiles or fabrics from bolts, rolls, spools, etc.

This invention has utility in the determination of uniform linear condition for the stock in producing a smooth roll, or for at once cutting into lengths of tubular knit stock, such as wrist-bands for gloves, under-garments, etc.

Referring to the drawings:

Figure 1 is a side elevation of an embodiment of the invention in a tubular knit stock handling apparatus, being a duplex installation for rewinding, with one of the rewinders idle and cutting occurring directly from the treatment;

Fig. 2 is a view on the line II—II, Fig. 1, looking in the direction of the arrow, showing the gravity holding directing guide;

Fig. 3 is a view on the line III—III, Fig. 1, showing the adjustable retarding rolls;

Fig. 4 is a section on the line IV—IV, Fig. 1, showing the steaming or moistening apparatus of the installation;

Fig. 5 is a detail view of one of the ironing rolls, parts being broken away;

Fig. 6 is a plan view of the apparatus of Fig. 1;

Fig. 7 is a view on the line VII—VII, Fig. 6, showing the stretching or driving rolls;

Fig. 8 is a view from the left in elevation of the cutting device used in connection with the apparatus;

Fig. 9 is a view of a rewound roll of material; and

Fig. 10 is a perspective view of a bundle of wristbands, showing their uniform character due to handling hereunder.

A main frame 1 is shown as provided at one end with an extension having thereon a pair of disks 2, central of each of which 50 horizontal disk 2 is an upstanding pin 3. These pins 3 serve to anchor rolls 4, 5, of the

material to be handled, herein shown as web tubing. The strip of stock passing from the respective rolls is conducted about vertical guide pins 6, 7, and there over 55 stationary guide bar 8. Crossing this directing guide bar 8, and resting by gravity thereon is bar 9 (Fig. 2) vertically slidable on central rod 10 as moved by handle 11. Terminal trunnions 12 on the bar 9, guided 60 by ways 13 in the frame 1 keep the bar 9 in parallelism with the bar 8. In starting the apparatus, the handle 11 may be conveniently used to shift the upper bar 9 so that the end of the stock may be drawn over 65 the bar 8.

The strip material from the rolls 4, 5, now pass to the gripping or retarding device. Shaft 14 is anchored by a pair of vertical rods 15, in position in the frame 1. 70 Loosely mounted on the shaft 14 is a pair of rolls 16. Loosely mounted on the rods 15 and parallel with the shaft 14 is an upper shaft 17 having thereon two loose rolls 18 opposing the rolls 16. Helical springs 19 75 on the rods 15 are adjustable by thumb nuts 20 for regulating the gripping action of the rolls 18 as to the rolls 16. Upwardly extending from between the rolls 18 is a rod 21 fast with the shaft 17. This rod 21 is bent at its upper end and anchored eccentrically of disk 22. This disk 22 has a handle 23 which may be rocked to lift the rod 21 and thus space the rolls 18 from the rolls 16, so that in starting the apparatus, the end of the material to be handled may conveniently be drawn into position.

The strip material from the gripping rolls passes over guide roll 24 (Fig. 6) and into slot 25 (Fig. 4) of oven or steamer vessel 26 having removable cover 27. In this vessel 26 is a steam coil 28 having spray openings 29 for jetting steam against the stock passing therethrough. A valve 30 may be manipulated to control the steam supply 90 to the coil 28 (Fig. 4). The material passing from the vessel 26 leaves by slot 31 similar to entrance slot 25. Any condensation in the vessel 26 may pass off by drain pipe 32. 95

In leaving the vessel 26, the stock passes under guide roll 33 (Fig. 6) and thence up

ward over upper ironing roll 34 and downward to loop around lower ironing roll 35.

As herein shown the ironing rolls 34, 35, are spaced from each other and heated by gas. Valve 36 in gas line 37 permits control of the main gas supply, while a valve 38 controls gas flow past each mixer 39 to perforate tube burner 40, one being in each end of each roll 34, 35. These rolls 34, 35, have shafts 41 mounted in anti-friction bearings 42, anchored by straps 43 to the frame 1.

Bearings 44, fast with the frame 1, position shafts 45, 46, carrying respectively leather faced driving gripping rolls 47, 48.

15 The compression action therebetween may be adjusted by the insertion or removal of shims 49 between the lower bearings 44 and the frame 1. Housing 50 protects gears 51, 52, respectively fast with the shafts 45, 46, 20 and in mesh with each other. Accordingly in the driving of the shaft 46 by pulley 53 from belt 54, the roll 47 as the follower roll has the same angular travel as the main or driving roll 48.

25 The stock 4, 5, from the ironing rolls is shown as passing upward over the upper driving roll 47 and thence to be firmly gripped between the roll 47 and the roll 48 to pass below the roll 48. From this point 30 of completion of the uniform stretching and ironing treatment, the stock 4 is shown as passing upward about guide roll 55 and thence about roll rewind core pin 56.

The rewind is shown as automatic in 35 action, without the introduction of tension, and still directly takes up the stock as delivered notwithstanding the enlarging diameter of the rewind spool or roll. Semicircular guide plates 57 have central flanges 58 forming a slot therebetween for one end of the core bolt 56 to protrude through, as the bolt rises in the slot due to spool growth from 40 the winding by resting on the stock 4 being drawn over the driving roll 47. To care for

45 different widths of stock, the outer pair of plates 57 is adjustable. Each plate 57 has a bracket 59 through which may extend a bolt 60 to be engaged by a winged nut 61 in clamping the plate in different positions 50 along slot 62 (Fig. 6). Opposing each plate 57 is a semicircular plate 63 spaced by a vertical slot having outward flanges 64. Brackets 65 anchor the lower portions of the plates 63 to the frame 1, while the tops are 55 rigidly spaced by brackets 66.

In starting the operation of the rewind, after the strip of stock has been threaded through the machine and past the driving rolls 47, 48, the end of the stock is wrapped about the bolt 56 and such bolt then dropped in the slots between the flanges 58, 64, and the slack taken up. As the machine is started, the normal operation of the roll 47 is a friction supporting tread coacting

against the lower side of the rewound roll, 65 rotating such roll at the true linear travel rate of the stock being steamed and ironed, as well as stretched, without any tension on such stock after passing the driving rolls 47, 48. As the rewound roll grows in 70 diameter, the bolt 56, slides upward in the slots between the plates 57, 63.

When the cutter attachment is connected and in operation, the second set of rewind plates is idle. The rewind plates are merely 75 guides, and the stock as passing therebetween automatically grows up into a smooth sided complete roll 67 (Fig. 9).

In mounting the cutter, it may be positioned on an extension 68 from the main 80 frame 1. In operating belt shifter 69 to cause pulley 70 on shaft 71 to drive the belt 54, there is simultaneous driving of belt 72, shaft 73 and belt 74, extending to cutter pulley 75. Clutch handle 76 may be operated 85 to connect the pulley 75 to drive the cutter shaft 77 for rotating adjustable arms 78. Axially of the shaft 77 between the pair of arms 78 is a cutting block 79 against which are thrown knives 80 in the operation of the 90 cutter to sever half loops of the stock as wrapped about the arms 78 (U. S. Patent 988,578, Laukhuff, Apr. 4, 1911). A pair of cams 81 one for each cutting operate the counter 82 for registering the number of 95 pieces being produced in the operation of the apparatus hereunder. These cuttings may be assembled, say in dozen pair lots, forming uniform bundles 83 (Fig. 10).

The operation of the installation hereunder is such that flimsy stock is taken, placed under a desired uniform tension, which may be such as to vary the width range 30%, and the stock, steamed and ironed, and then rolled or cut as of uniform character 105 linearly.

What is claimed and it is desired to secure by Letters Patent is:

1. A material treating apparatus for strip fabric embodying a frame, a pair of opposing gripping rolls carried by the frame for receiving material therebetween; a steaming chamber carried by the frame adjacent the rolls, a pair of ironing rolls, and a pair of drawing rolls therebeyond, said ironing and 110 drawing rolls being also carried by the frame, said drawing rolls being operable for pulling material through the receiving rolls, through the chamber and about the ironing rolls.

2. A material treating apparatus frame, and strip fabric conducting and treating means carried by the frame, including in sequence material gripping receiving rolls, a moistening chamber, ironing mechanism, a 115 pair of drawing rolls, and a rewind mechanism embodying a guide for directing a roll to be rewound to ride on the fabric on its

way to said rewinding, said fabric being positively driven, after said rewind driving contact, by passing between said drawing rolls.

5. 3. A rewind mechanism embodying a pair of drawing rolls, a fixed guide directed toward one of said rolls for holding a roll of

material to be rewound toward said roll, and conducting means for the material passing such material to be contacted by the rewound 10 roll before passing between the drawing rolls.

In witness whereof I affix my signature.

HERMAN A. GILLIAN.
